SPRAY COATING MACHINE

Filed Sept. 27, 1928

UNITED STATES PATENT OFFICE

HERBERT L. CHAPIN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

SPRAY COATING MACHINE

Application filed September 27, 1928. Serial No. 308,796.

This invention relates to spray coating machines and is herein illustrated as embodied in a machine of the type disclosed in Letters Patent of the United States No. 1,311,161, granted July 29, 1919, on application of Frederick M. Furber, for coating shoe parts with blacking or other stains.

Machines of this character, in which the liquid is sucked up from an open receptacle through an upright pipe and ejected in a downwardly directed spray, have found wide application in shoe factories for the coating of the margins of shoe soles, and in particular they have been found desirable for applying a marginal stripe of blacking to the upper or flesh surface of a sole which is to be embodied in a McKay shoe prior to its incorporation in the shoe. For this purpose such machines have been provided with means for controlling the width of the marginal stripe and for regulating the fineness and volume of the spray.

In an improved machine of the type referred to above, a gaging means in the form of a sleeve surrounding the upright pipe has been provided, as shown in Letters Patent of the United States No. 1,376,524, granted May 3, 1921, on application of F. M. Furber, and this sleeve is so mounted that it may be adjusted toward and away from the path of the spray thereby to vary the width of the marginal stripe applied to the sole. A guard plate has also been employed, positioned at the other side of the spray from this gaging means, by means of which the distance of the work from the spraying nozzle could be controlled and drops of liquid directed toward the inner margin of the stripe deflected so as thereby to define the margin.

One object of the invention is to provide a machine of the type referred to having an improved spray guard, by means of which the width of the marginal stripe of liquid applied to the work may be still more accurately controlled and the inner edge of the stripe more sharply defined, further to facilitate applying a narrow stripe of coating.

In accordance with features of the invention the illustrated machine comprises a spray guard which is constructed and ar-

ranged so that not only may the stripe be sharply defined but the width of the marginal stripe may be adjustably determined, spattering of the liquid prevented and excess liquid carried off to one side. In the 55 illustrated arrangement, a spray guard partially surrounding a downwardly directed spray has an inclined upper surface cut away to form a U-shaped opening with the base of said opening provided with a sharpened 60 edge intercepting part of the spray and arranged to define the width of the marginal stripe of blacking. The legs of the U are arranged to drain the intercepted blacking to one side away from the work and the up-standing sides of the guard are arranged to prevent spattering.

When a guard plate is interposed in the path of the spray of liquid, it is found that there is some tendency for the liquid to collect 70 on the under side of the plate and to drip from the plate on the work. In accordance with another feature of this invention, such dripping on the work is prevented by arranging the under surface of the guard adjacent to the edge which is interposed in the path of the spray so that that surface is either inclined toward the intercepting edge, or is at least at right angles to the path of the spray, 75 it being illustrated as horizontal when the spray is projected downwardly, as shown. By this arrangement any tendency for the collection of drops upon the under surface of the guard is avoided.

Still another object of the invention is to 85 provide improved mechanism by means of which the quantity of spray and its character, as a fine or a coarse spray, may be more readily controlled.

One highly satisfactory arrangement for 90 controlling the spray is illustrated in Letters Patent of the United States No. 1,571,939, granted Feb. 9, 1926, upon the application of F. M. Furber. In that mechanism, a casing 95 communicating with the supply of air and the supply of liquid is provided with an upright passage which is filled by an adjustable hollow valve stem having a spray nozzle. The jet opening is controlled by means of a 100 removable and adjustable nipple. In ac-

cordance with other features of the present invention, an improved control mechanism is provided which, as illustrated, includes a rotatable valve stem fitting the longitudinal passage just mentioned and having therein an integral atomizing chamber the outlet of which is controlled by a removable nipple having a jet opening. By providing a variety of nipples in which the size of the jet opening and the position of the jet opening with respect to the spray nozzle in the valve stem are different, the valve stem may be adapted for conveniently and accurately controlling the character of the spray. At the same time, the illustrated construction and arrangement are such that the quantity of spray may be simply and accurately controlled by mere rotation of the valve stem. Moreover, the illustrated machine is organized to permit the valve stem to be removed axially but only when it is in such position that the air passage is closed.

These and other features of the invention are described in the following specification and illustrated in the accompanying drawings, in which,

Fig. 1 is a perspective view of the spraying mechanism including the spray guard showing a piece of work presented in operative position,

Fig. 2 is a side elevation of the same parts with the upper portion of the spraying apparatus and the guard shown in vertical section,

Fig. 3 is a perspective view of the valve stem removed from the casing,

Fig. 4 is a horizontal section looking upward on the line IV-IV of Fig. 2,

Fig. 5 is a horizontal section on the line V-V of Fig. 2, and

Fig. 6 shows in enlarged section other forms of nipples having different sizes and types of jet openings.

The spraying apparatus shown in Figs. 1 and 2 is mounted at the outer end of an arm 10 having a conduit 12 through which air under pressure is supplied during the operation of the machine. The outer end of the arm 10 is provided with a vertical passage 14 for the reception of an upright portion 16 of a casing 18. This upright portion of the casing 18 is drilled vertically to receive a rotatable hollow valve stem 20 and has a lateral opening 22 for the admission of air to a passage in the hollow valve stem which will be later described. The casing 18 is also provided with a depending pipe 24 which dips in liquid, such as blacking 26, in a receptacle 28 and has an internal vertical passage 25. Clamped on the lower end of the pipe 24 is a strainer 30. Above this strainer is a hollow support 32 split at the upper end and provided with a clamp bolt 34 for the reception of, and for the holding in position of, a sleeve gage 36. This sleeve

gage 36 is cut away at 37 to avoid interference with the valve stem 20 and may be moved radially of the pipe 24, toward and away from the path of the spray delivered from the valve stem 20. The edge of a piece of work, such as a sole 38, is rested against the gage as shown in Figs. 1 and 2 thus determining the position of the work with respect to the path of the spray.

The upright portion 16 of the casing 18 is fastened in position at the outer end of the arm 10 by means of a clamp nut 40 and suitable gaskets 42 and 44 to prevent leakage are interposed between the arm 10 and the casing. The clamp nut 40 also serves to hold in position a washer-like portion of a locking device 46 having a headed stud 48 which cooperates (Figs. 1 and 2) with a flange 50 formed on the under side of the handle 52 of the valve stem 20. The construction of the flange 50 is such that the valve stem can only be removed from the casing when an arrow 54 (Fig. 1) on the upper side of the handle 52 is turned half way around from the locking stud 48 so that the air supply is shut off, as later described. When the arrow points toward the stud 48, the air supply is wide open. It will be noted from Figs. 2 and 3 that the flange 50 is provided with a stop 56, which, by contact with the stud 48, after rotation clockwise, denotes that the valve stem is in such a position that the supply of blacking is completely cut off.

The valve stem 20 has a longitudinal passage 60 communicating at its upper end with a recess 62 which has an enlarged portion 64 (Fig. 5) so that the passage 60 is in communication with the air inlet 22 in any position of adjustment of the valve stem in which the blacking supply is available. The passage 60 terminates at its lower end in an atomizing chamber 66 formed within the valve stem itself, and the lower end of the passage 60 emerges from a nozzle 68 of conical form which projects down into the atomizing chamber below the level of a lateral liquid inlet 70. This opening communicates with a horizontal passage 72 which opens into the vertical passage 25 in the upright pipe 24. When the valve stem is turned to such a position that the arrow points diametrically away from the stud 48, then the air and blacking supplies will both be shut off and the valve stem may be removed, if desired, without danger.

The lower end of the atomizing chamber 66 is closed by means of a nipple 74, which is designed to produce a fine spray. As shown in Figs. 2 and 3, this nipple 74 is counterbored at its upper and lower sides to form a central partition having a jet opening 76 of small size. The character of the spray may be controlled by changing the nipple 74 to a nipple 78, as shown in Fig. 6, which is counterbored only at its upper side and provided with a

jet opening 80 having a longer passage but of the same size as the opening 76 thereby to emit a medium spray. Still another form of nipple 82 having a larger jet opening 84 with a still longer passage may be employed when it is desired to get a coarse spray, the control of the character of the spray being determined by the relation of the jet opening to the end of the nozzle 68 and by the size of the jet opening.

In the atomizing chamber 66 a partial vacuum is formed by the air blast emitted from the nozzle so that atmospheric pressure upon the liquid 26 in the reservoir 28 forces it up through the pipe 24 into said atomizing chamber. Since the liquid enters at a point opposite the side of the nozzle 68 and above the air opening in said nozzle, it is broken up into a fine mist before it is driven out through the jet opening 76.

Having provided the valve stem 20 with a nipple of the desired kind to get a fine or a coarse spray, as may be desired, which may be readily done by removing the valve stem 20, then the operator has only to turn the handle 52 thereby to control the quantity of liquid driven out. It will be seen that the illustrated construction is simple and provides for an accurate and quick adjustment of the quantity of spray emitted without requiring extensive experience.

In order that the leakage of air may be reduced to a minimum, each individual valve stem 20 is preferably ground to fit the bore of the corresponding casing 18, but even with this precaution, there is some danger of the leakage of air around the outside of the valve stem, and if this leakage occurs in sufficient volume, it will destroy the vacuum in the atomizing chamber 66 and prevent the lifting of liquid from the receptacle. In order to avoid this danger, the valve stem 20 is provided between the recess 62 and the nozzle 68 with a bleeder groove 86 communicating with the atmosphere by means of a vertical groove 88. Thus any air leakage around the valve stem 20 will be collected in the groove 86 and allowed to leak into the atmosphere through the groove 88 without entering the horizontal air passage 72 or the atomizing chamber 66.

In order that the operator may have full control of the width of the marginal stripe 90 of blacking applied around the upper surface of the sole 38 and so that he may make it quite narrow if desired, the machine is provided with a spray guard 92, the edge of which is interposed in the path of the spray to intercept a portion thereof. This guard is arranged in a manner to be later described for lateral adjustment into and out of the path of the spray, and is provided with a U-shaped recess terminating at the bottom of the U in a sharp edge 94 produced by relatively inclined surfaces. The upper or inner sur-

face 96 of the guard is arranged at an acute angle to the direction of the spray, while its bottom or outer surface 98 is disposed substantially at right angles to the path of the spray, or in the arrangement herein shown, in a substantially horizontal position. By placing this sharpened edge at the desired position in the spray, the operator can control accurately the width of the marginal stripe, inasmuch as the guard prevents spreading of the spray at that side of the spray path. By reason of the relation of the under surface 98 of the guard to the path of the spray there is no tendency for the drops of liquid to collect on said surface, which might otherwise form and be carried off onto the work. Spattering of the operator or the work by deflected particles of spray striking the inclined upper surface 96 is prevented by the surrounding front flange 100 and the side flanges 102. These side flanges are slotted at 104 so that the guard may be adjustably secured to the casing 18 by screws 106. The horizontal disposition of the slots 104 allows the guard to be adjusted toward and away from the vertical path of the spray to vary the width of the marginal stripe of blacking. Any liquid accumulating on the upper surface 96 will be carried off by the lateral drains 108 formed in the sides of the U-shaped guard and dropped off into the receptacle 28 at a point out of the range of the work. It will be observed that the guard 92 where its under surface 110 contacts with the upper corner of the sole 38, serves to gage the distance between the sole and the jet opening 76. The lower end of the gage sleeve 36 is cut away at 112 and the adjacent support 32 is cut away at 114 in inclined relation to the path of the spray, thus avoiding danger of spattering by reason of the interception of particles of the spray, as would be the case if these surfaces were horizontal.

In using the machine, the operator selects the nozzle 74, 78 or 82, depending on whether he desire a fine, medium or coarse spray, and adjusts the gage sleeve 36 and the spray guard 92 to get the desired width of coating upon the margin of the work 28. Having turned the valve stem 20 by means of the handle 52 to connect the passage 60 with the air in the opening 22 so as to direct a blast of air through the nozzle 68 into the atomizing chamber 66, and thence out through the jet opening 76, this current of air will set up a partial vacuum in the atomizing chamber 66 which will cause liquid to flow through the upright passage 25 and the horizontal passage 72 into the liquid opening 70 of the atomizing chamber. Adjustment of the position of the handle 52 will enable the operator to set the machine to deliver the desired quantity of liquid against the work by varying the relation of the opening 70 to

the passage 72. This will not vary the air pressure, however, because of the enlarged portion 64 of the air inlet opening.

Having thus described my invention what I claim as new and desire to secure by Letters Patent of the United States is:

1. In a spray coating machine, a spraying apparatus and a spray guard interposed in the path of the spray to intercept and to remove a portion thereof, said spraying apparatus and guard being relatively adjustable to define the width of the spray applied to the work.

2. In a spray coating machine, a spraying apparatus and a spray guard interposed in the path of the spray and formed and arranged to intercept a portion thereof and to return the intercepted portion to the spraying apparatus, said guard being adjustable laterally of the path of the spray and having a sharpened edge thereby to define the margin of the coating produced by the spray.

3. In a spray coating machine, a spraying apparatus and a spray guard partially interposed in the path of the spray and having a sharpened edge produced by relatively inclined surfaces, the inner of which lies at an acute angle to the direction of the spray to intercept and to capture a portion thereof and the outer of which lies substantially at right angles to the path of the spray.

4. In a spray coating machine, a spraying apparatus arranged to project a spray downwardly and a spray guard having a spray deflecting surface partially interposed in the path of the spray to intercept a portion thereof thereby to limit the amount of spray applied to the work, and having a sharply defined edge portion, the under surface of said guard being substantially horizontal thereby to prevent the collection of liquid upon said under surface.

5. In a spray coating machine, a spraying apparatus and a spray guard partially interposed in the path of the spray to cut off a portion thereof, said guard having upstanding lateral portions partially surrounding the spray to intercept spatters of blacking from the upper surface of the guard and thereby to protect the operator and the work.

6. In a spray coating machine, a spraying apparatus and a spray guard partially interposed in the path of the spray, said guard being provided with an upper surface inclined with respect to the path of the spray and partially surrounding the spray, one portion of said guard surface intercepting a portion of the spray from being applied to the work thereby to define the margin of the coating applied to the work.

7. In a spray coating machine, a spraying apparatus and a spray guard partially interposed in the path of the spray, said guard being provided with an upper surface, one portion of which is interposed in the path of

the spray and other portions of which are formed with lateral drains to conduct blacking accumulated on the upper surface of the guard to a point outside the path of the spray.

8. In a spray coating machine, a spraying apparatus and a spray guard partially interposed in the path of the spray, said guard partially surrounding the spray and having an upper surface, one portion of which is interposed in the path of the spray, and lateral portions extending from said first-mentioned portion to points outside the path of spray, said lateral portions having drains formed therein to conduct accumulations of liquid away from the work.

9. In a machine for applying a stripe of blacking to the margin of one surface of a shoe sole, a spraying apparatus constructed and arranged to project a jet of blacking, gage means disposed at one side of the path of the spray jet against which the edge of the sole may be rested as it is guided through the spray, and a guard positioned opposite said gaging means and having an opening formed therein the edge portion of which is interposed in the path of the spray to intercept a portion of the spray, thereby to determine the width of the margin of blacking applied to the sole.

10. In a machine for applying a stripe of blacking to the margin of one surface of a shoe sole, a spraying apparatus constructed and arranged to project a jet of blacking in a downward direction, gage means disposed at one side of the path of the spray jet against which the edge of the sole may be rested as it is guided through the spray, and a guard disposed opposite said gaging means and having a sharpened edge portion interposed in the path of the spray and formed by an inclined upper spray deflecting surface and a substantially horizontal lower surface.

11. In a machine for applying a stripe of blacking to the margin of one surface of a shoe sole, a spraying apparatus constructed and arranged to project a jet of blacking in a downward direction, gage means disposed at one side of the path of the spray jet against which the edge of the sole may be rested as it is guided through the spray, and a guard disposed opposite said gaging means and having a sharpened edge portion interposed in the path of the spray and formed by an inclined upper surface and a substantially horizontal lower surface, said inclined upper surface having lateral drains constructed and arranged to lead away accumulations of blacking on said surface to a point beyond the edge of the sole being coated.

12. In a machine for applying a stripe of blacking to the margin of one surface of a shoe sole, a spraying apparatus constructed and arranged to project a jet of blacking, and a guard having a U-shaped opening the base of which is interposed in the path of

the spray, thereby to determine the width of the margin of the blacking applied to the sole, said guard being arranged with its legs surrounding said jet of blacking and constructed and arranged to drain off the accumulation of blacking on the upper surface of the guard. 5

13. In a machine for applying a stripe of blacking to the margin of one surface of a shoe sole, a spraying apparatus constructed and arranged to project a jet of blacking, gage means disposed at one side of the path of the spray jet against which the edge of the sole may be rested as it is guided through the spray, said gaging means comprising a cylindrical member disposed alongside the path of the spray, and a guard having a U-shaped opening the base of which is interposed in the path of the spray, thereby to determine the width of the margin of the blacking applied to the sole, said guard being arranged with its legs surrounding said cylindrical gaging means and constructed and arranged to drain off the accumulation of blacking on the upper surface of the guard. 10

14. In a machine for applying a stripe of blacking to the margin of one surface of a shoe sole, a spraying apparatus constructed and arranged to project a jet of blacking, gage means disposed at one side of the path of the spray jet against which the edge of the sole may be rested as it is guided past the spray, said gaging means comprising a cylindrical member disposed alongside the path of the spray, and a guard adjustably secured to said spraying apparatus and having a sharpened edge portion interposed a predetermined distance in the path of the spray to determine the width of the margin of blacking applied to the shoe sole. 15

15. In a spraying apparatus, a casing having a longitudinal passage provided with a lateral air inlet and with a lateral liquid inlet, and a rotatable valve stem in said passage having a spray nozzle communicating with said air inlet in a plurality of positions of adjustment of said stem and an internal atomizing chamber having a lateral opening therein disposed opposite said liquid inlet, and means for rotating said valve stem in said casing to control the amount of liquid admitted to said passage by varying the area of the liquid inlet while keeping constant the air inlet and the area of the internal atomizing chamber. 20

16. In a spraying apparatus, a casing having a longitudinal passage provided with a lateral air inlet and with a lateral liquid inlet, a rotatable valve stem in said casing having an internal atomizing chamber, a longitudinal passage terminating in a spray nozzle and connecting the atomizing chamber with the air inlet in a plurality of positions of adjustment of the stem, and a liquid opening in said chamber disposed opposite the

liquid inlet whereby rotation of said valve stem is effective to vary the position of the opening in said chamber relatively to said liquid inlet to control the quantity of liquid admitted to said atomizing chamber without varying the quantity of air admitted to the spray nozzle. 70

17. In a spraying apparatus, a casing having a longitudinal passage provided with a lateral air inlet and with a lateral liquid inlet, and a rotatable hollow valve stem fitting said longitudinal passage and having a spray nozzle, a removable nipple carried by said valve stem and having a jet opening, a liquid inlet in cooperative relation to said spray nozzle, and a lateral opening communicating with the air inlet, whereby said valve stem is constructed and arranged to control the quantity of liquid admitted to the spray nozzle by rotation of the valve stem without changing the relative positions of the spray nozzle and the jet opening. 75

18. In a spraying apparatus, a casing having a longitudinal passage provided with a lateral air inlet and with a lateral liquid inlet, a hollow valve stem filling said passage and having lateral openings communicating with said air inlet and said liquid inlet, said valve stem having an internal atomizing chamber in which there is provided a spray nozzle adjacent to the liquid opening and a terminal jet opening communicating with said chamber, and means for varying the position of said valve stem to determine the area of the liquid opening, thereby controlling the quantity of liquid admitted to the atomizing chamber without varying the area of the atomizing chamber or the air pressure admitted to said chamber. 80

19. In a spraying apparatus, a casing having a longitudinal passage provided with a lateral air inlet and with a lateral liquid inlet, and a hollow valve stem filling said passage and having an atomizing chamber and lateral openings communicating with said liquid opening and said air opening, said valve stem also having a bleeder passage surrounding the stem between the air opening and the liquid opening and communicating with the atmosphere, thereby to prevent leakage of air around said stem from entering the atomizing chamber. 85

20. In a spraying apparatus, a casing having a longitudinal passage provided with a lateral air inlet and with a lateral liquid inlet, a hollow valve stem having a spray nozzle and arranged to communicate with said inlets, means for varying the position of the valve stem with respect to said inlets, and means for preventing removal of the valve stem when in a position to admit air to the nozzle. 90

In testimony whereof I have signed my name to this specification.

HERBERT L. CHAPIN. 130
